Morris Hirsch.

UNITED STATES PATENT OFFICE.

PAUL IRIBE, OF NEW YORK, N. Y.

DESIGN FOR A PHONOGRAPH-CABINET.

55,863.

Specification for Design.

Patented July 20, 1920.

Application filed May 12, 1920. Serial No. 380,922. Term of patent 14 years.

To all whom it may concern:

Be it known that I, PAUL IRIBE, a citizen of the Republic of France, residing at New York city, in the county of New York and State of New York, have invented a new, original, and ornamental Design for Phonograph-Cabinets, of which the following is a specification, reference being had to the accompanying drawing, forming part thereof.

The figure is a side elevation of a phonograph cabinet showing my new design.

I claim:

The ornamental design for a phonograph cabinet, as shown.

PAUL IRIBE.
